ROTARY TOOTHBRUSH

Pat M. Bredon, 3518 Crittenden, St. Louis, Mo.

Filed Jan. 29, 1962, Ser. No. 68,549

Term of patent 14 years

(Cl. D9—2)

FIG. 1

FIG. 2

FIG. 3

FIG. 4

FIG. 5

FIG. 1 is a side elevation of a rotary toothbrush showing my new design;

FIG. 2 is a top plan view thereof;

FIG. 3 is a bottom plan view thereof;

FIG. 4 is a front elevational view thereof; and

FIG. 5 is a rear elevational view thereof.

The side not shown is substantially the same in appearance as that disclosed in FIG. 1.

I claim:

The ornamental design for a rotary toothbrush, as shown and described.
